UNITED STATES PATENT OFFICE

2,277,495

TRAFFIC CONTROL SYSTEM

Copeland MacAllister, Winchester, Mass., assignor to General Electric Company, a corporation of New York

Application December 4, 1941, Serial No. 421,669

3 Claims. (Cl. 177—337)

My invention relates to traffic control systems and more particularly to a traffic control system comprising a group of intersection controllers controlled by a common master controller and interconnected therewith by a relatively long control cable.

One object of my invention is to provide an interconnecting control cable in which voltages induced in the idle conductors of the cable by control impulses sent out over the periodically selected conductors of the cable are made ineffective to operate apparatus controlled through the idle conductors.

For a better understanding of my invention, together with other and further objects thereof, reference is had to the following description taken in connection with the accompanying drawing, and its scope will be pointed out in the appended claims.

The accompanying drawing illustrates diagrammatically a traffic control system embodying my invention.

Referring to this drawing in detail, a master controller 10 is connected to control secondary controllers 11 of which only one is illustrated in this drawing, the connecting conductors to one other secondary controller being indicated. The secondary controller 11 operates groups of traffic signals 12 and 12' which are connected to the controller is preferably of the type fully described controller by a suitable cable 13. The secondary in application S. N. 416,969, filed October 29, 1941, by R. A. Reid. This controller includes a suitable contact mechanism for sequentially energizing the signals 12, 12'. This mechanism may be of any well-known construction and is indicated merely by a rectangle 11'. Its operation is controlled by a timing dial 14 mounted on a shaft 15 and driven by a motor 16 through its shaft 17 and a pair of cooperating gears 18 and 19. The timing dial is provided with two concentric rows of radial slots 20 and 21 in each of which a group of keys or switch actuators is spaced in accordance with a desired program. Keys 22 to 26 are provided in the outer row of slots and keys 27 to 31 are provided in the inner row of slots for respectively actuating switch contacts 32 and 33. The switch contact 32 is mounted upon a suitable resilient contact arm 34 to the free end of which is attached an actuating block 35. The end of the actuating block projects into the path of the actuators in the outer row of slots 20, and as each actuator passes the actuating block, the contact is raised to engage a cooperating contact 36 thereby establishing a circuit from a common

conductor 37, which is connected to a source of power and from which current is supplied, through conductors 38 and 39 to the contact 36. The circuit continues from contact 36 to contact 32, contact arm 34, conductor 40 to a switch terminal 41.

The inner row of actuators, 27 to 31, actuate the contact 33 which is mounted upon a resilient contact arm 42 mounted parallel to the contact arm 34 and is provided with an actuating block 43. As the actuators 27 to 31 move under the end of the actuating block 43 the actuating block with the contact 33 is raised to engage a contact 44 thereby to close a circuit from the conductor 37 through conductors 38, 39 and 45 to the contacts 44, 33, contact arm 42, conductor 46 to switch 47 and from switch 47 to the contact mechanism 11' through a conductor 48.

The switch 47 is a two-position switch which may be moved from the position in which it is illustrated to a position in which it engages the terminal 41. In case the switch is so moved the circuit between conductors 46 and 48 is broken by the switch and a circuit is established between the conductor 40 and the conductor 48. When the switch 47 is in the position illustrated, the inner row of actuators is effective to operate the contact mechanism 11', the operating circuit being established from the source conductor 37 through the second pair of contacts 44, 33 to the controller. In the second position of this switch 47 the operating circuit to the switch mechanism may be completed by the first pair of contacts 32, 36 actuated by the outer row of actuators on the timing dial. Since each group of actuators is arranged in accordance with a predetermined program, the switch 47 is the secondary program selector switch.

The program switch 47 is operated by magnets 50 and 51 which actuate through their respective armatures a link member 52 connected to the armatures and to the switch 47. When coil 50 is energized, the link member is drawn upwardly to place the switch in the position shown, and when coil 51 is energized, the link and switch are drawn downwardly to establish a circuit between contact 41 and the conductor 48. The coil 50 is connected by a conductor 53 to a common conductor 54 of the interconnecting cable for the system. This common conductor is one of several conductors which connect this controller to the master controller 10. Other controllers are connected to these conductors as indicated, for example, by the conductor 53'. This conductor 54 terminates in the master controller at con-

tacts 55 and 56 of a relay 57. This relay 57 is provided, in accordance with my invention, to connect the conductor to a source of power when a control impulse is to be sent from the master controller to the secondary controllers and to connect this conductor to ground when the control impulse is ended.

The relay 57 is provided with an operating coil 58 which is energized by the operation of a master selector switch 59. When this switch is in the position in which it is shown in the drawing, it completes a circuit to the coil 58, through a conductor 60 from the source conductor 37. The coil is grounded at its opposite end. When the coil is so energized the relay is operated to close a circuit to the conductor 54, through terminals 55, 61, conductor 60 and source conductor 37. The secondary controller coils 50, being connected to the conductor 54 through conductors 53, 53', are each energized to move the corresponding secondary selector switch 47 to its upper position. When the master switch 59 is opened to deenergize the coil 58, the relay is operated to close a circuit from the terminal 56 to a terminal 62 and through a conductor 63 to ground.

The coil 51 of the secondary switch 47 is connected by a conductor 64 to a second common conductor 65 which extends to the master controller terminating in contacts 66, 67 of a relay 68, which relay, being in a deenergized position, establishes a circuit to ground through its contacts 67, 69 and grounded conductor 70. The coil 71 of this relay is grounded at one end and at the other end is connected by a conductor 72 to a contact 73 of the switch 59. This manually operated master selector switch 59 may be moved to engage this contact 73 thereby to energize the relay coil 71 from the source conductor 37 through the conductor 60. When so energized, the relay 68 is operated to establish a circuit from the contact 66 and the conductor 65 to a contact 74 and through a conductor 75 to the conductor 60 thereby completing the circuit from source conductor 37 to the coil 51 which is grounded at its opposite end.

The motor 16 is normally driven by a field 76 energized from the source conductor 37 through the conductor 38, a conductor 77 and a manually operated switch 78. The motor is also provided with a braking field 80 which when energized tends to drive the motor in an opposite direction and thereby holds the motor stationary when field 76 is energized. This field is energized only when the dial 14 is not in its proper operating relation to the master controller and is energized by the movement of a special key 81 placed in the inner row of slots 21 to actuate an actuating block 82. This key is provided with a slot 81' so that it will not actuate the actuating block 43. The actuating block 82 is attached to a contact arm 83 which is mounted parallel to contact arm 42 and carries a contact 84. When the contact 84 is raised it engages a cooperating contact 85 to establish a circuit to the field 80 which may be traced from the grounded end of the field 80 through the field to a conductor 86, the contacts 84, 85, contact arm 83, conductor 87 to a common conductor 88 terminating at the master controller at contacts 89, 90 of a relay 91. The relay is in its energized position and connects contact 89 to a contact 92 which is connected by a conductor 93 to the conductor 60 and thereby to the source conductor 37. The relay 91 is provided with an operating coil 94

which is grounded at one end and receives energy through a conductor 95, a pair of closed contacts 96, 97, conductor 60 and source conductor 37. The contacts 96, 97 are normally closed. Contact 96 is, however, mounted upon a supporting arm 98 which is raised by a cam 99 provided with a projection 100. This operation is such that the contacts are separated momentarily once during each cycle of traffic signal operations. When the contacts are separated the coil 94 is deenergized thereby dropping the relay to its second position at which the conductor 88 is connected to ground through contact 90, relay 91, contact 102 and grounded conductor 103. Under proper operating relationship, that is when the controllers are in synchronism, the actuating key 81 closes the circuit for field 80 by the actuation of the contact 84 at the same instant that the cam projection 100 effects a separation of the contacts 96, 97, thereby opening the circuit to the field 80 at the instant at which the secondary controller attempts to close it. The secondary controller thereby is permitted to continue operation whereby it again opens the circuit at the contacts 84 and 85 and the reclosure of the master contacts 96, 97 becomes ineffective to stop the dial 14. In case the dial 14 and the cam 100 are out of proper operating relationship or out of synchronism, the circuit to field 80 is completed and the dial 14 is held stationary with the contacts 84, 85 closed until the cam 100 is rotated to the position at which it separates the contacts 96, 97.

The relays 57, 68 and 91 are provided in the common conductors 54, 65 and 88 in accordance with my invention. The operating coil of each of these relays is energized when it is desired to send out a control impulse over its respective common conductor, the relay being thereby operated to connect its common conductor to a source of power. The coil is deenergized when the control is effected. The relay then breaks the connection between its conductor and the source of power and establishes a circuit to ground for its conductor. In the drawing, the conductor 65 is grounded while the conductors 54 and 88 are energized through the relays 57 and 91. When selector switch 59 is moved to its second position to engage the contact 73, the coil 58 of the relay 57 becomes deenergized and the relay drops to establish a circuit to ground for the conductor 54. The relay coil 71 is then energized through the switch 59, breaks its ground circuit to the conductor 65 and establishes a current path through its contacts 66, 74 to the conductors 75, 60 and 37.

It has been found that in long cables to which other controllers may be connected by groups of conductors such as 38', 53', 64' and 81', the capacitative inductance between conductors is of such magnitude that when one of the conductors of the cable is energized or deenergized, an induced voltage arises in the other conductors, which are idle at that instant, which voltage is at times great enough to operate the selector switches or other apparatus connected to these conductors in the secondary controllers. In accordance with my invention the relays that are provided at the master controller for each conductor of the interconnecting control cable connect each conductor to ground, except the one which is energized to effect a control operation. All induced currents in the idle conductors are thereby immediately discharged to ground and their potential does not build up sufficiently

to effect an actuation of the apparatus connected thereto.

What I claim as new and desire to secure by Letters Patent of the United States is:

1. In a traffic signal system, the combination of a master controller, a secondary controller, conductors interconnecting said controllers, means in said master controller for periodically energizing said conductors individually, and means in said master controller for grounding said conductors respectively at the end of each energization period.

2. In a traffic signal system, the combination of a master controller, a group of secondary controllers, conductors interconnecting said controllers, master switches in said master controller, and relays between said master switches and said conductors arranged normally to estab-

lish a ground connection for each of said conductors, and successively to break said ground connections responsive to the operation of said respective master switches and to connect said conductors to a source of current.

3. In a traffic signal system, the combination of a master controller, a group of secondary controllers, conductors interconnecting said controllers, relays in said master controller arranged individually to connect said conductors to ground and when energized to break said ground connection and to establish a connection between said conductors and a source of energy, and means in said master controller for periodically energizing the operating coils of said relays thereby to break said ground connection and to connect said conductors to a source of energy.

COPELAND MacALLISTER.

CERTIFICATE OF CORRECTION.

Patent No. 2,277,495.

March 24, 1942.

COPELAND MacALLISTER.

It is hereby certified that error appears in the printed specification of the above numbered patent requiring correction as follows: Page 1, first column, line 30, strike out "controller is preferably of the type fully described" and insert the same after "secondary" in line 31; and that the said Letters Patent should be read with this correction therein that the same may conform to the record of the case in the Patent Office.

Signed and sealed this 19th day of May, A. D. 1942.

(Seal)

Henry Van Arsdale,
Acting Commissioner of Patents.
